SPARK PLUG

Willard E. Lyons, Chicago, Ill., assignor to Harry S. Harned, Oak Park, Ill.

Application September 8, 1933, Serial No. 688,592

8 Claims. (Cl. 123—169)

This invention relates to improvements in spark plugs and more particularly to a plug of the character in which there is provided an air gap at the outer end of the plug to intensify the spark at the main spark gap between the electrodes at the inner end of the plug, and one of the objects of the invention is to simplify the construction as well as reduce the cost of production of a plug of this character, as well as improve the appearance and increase the attractiveness thereof.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

20 Figure 1 is an elevation of a plug of this character constructed in accordance with the principles of this invention.

Figure 2 is a detail sectional view on an enlarged scale, and as taken on line 2—2, Figure 1.

25 Figure 3 is a view similar to Figure 2, showing some of the associated parts of the plug separated.

Figure 4 is a top plan view of Figure 2, with the binding nut omitted.

30 Referring more particularly to the drawing the numeral 10 designates the usual shell of a spark plug provided with exterior threads 11 adjacent one end thereof.

The numeral 12 designates the core of insulating material, such as porcelain or glass which is secured in the shell 10 in the usual manner, such as by means of the gland 13.

35 The core 12 is provided with a centrally disposed opening 14 therethrough and in which opening is arranged the central conductor 15, which projects for a substantial distance below the core to form one of the electrodes of the spark gap at the inner end of the plug.

This conductor 15 is held in position by means 40 of a stem 16 provided with exterior threads 17 so as to be threaded into the end of the core 12. The conductor 15 is secured to the stem 16 in any suitable manner and the stem is provided with a flange 18 extending therearound, and 45 which flange is of any desired diameter less than the external diameter of the adjacent portion of the core 12. The flange 18 is located intermediate the ends of the stem 16, and the upper end of the stem may be reduced in diameter as at 19.

The numeral 20 designates a member which is constructed of a phenolic condensation product, commonly known as bakelite, and the upper end of the stem 16 is threaded into the member 20. The member 20 may be provided with a recess 21 in its lower face, and into which recess the flange 18 projects, there being projections 22 extending above the upper surface of this flange, which are seated in the body portion of the member 20 to hold the member 20 against rotation with respect to the core 12, and any number of projections 22 may be provided.

The member 20 is preferably of a diameter substantially equal to the diameter of the adjacent portion of the core 12.

50 The stem 16 together with the flange 18 are constructed of any suitable metal to form a continuation of the central conductor 15.

A second stem 23 constructed of any suitable metal and similar in construction to the stem 16, is provided with exterior threads 24, which are threaded into the upper end of the member 20. The stem 23 is provided with a flange 25 extending therearound and of any desired diameter, but 55 is of a diameter considerably less than the exterior diameter of the member 20. Projections 26 are provided on the lower face of the flange 25 which are adapted to be seated in recesses in the upper end of the member 20 so as to hold the member 20 and the stem 23 against relative rotation.

The inner end 27 of the stem 23 may be reduced in diameter as desired and when in position and when the flange 25 rests upon the top of the member 20, the extremity 27 of the stem 23 will terminate short of the extremity 19 of the stem 16 to form an air gap 28 therebetween, and the length of the gap is determined by the 60 space between the proximate extremities of the stems 16 and 23.

A clamp or binding nut 29 may be threaded on to the stem 23 and serves as a means for securing the high tension cable to the plug.

65 With this construction it will be manifest that a very simple arrangement will be provided and by reason of the employment of the member 20 constructed of a phenolic condensation product, it is possible to color the member with any suitable coloring matter and thereby not only produce a contrast between the core 12 and the member 20, but provide a rigid and strong construction.

70 At the same time the parts are so arranged 75

that they may be readily assembled and the cost of production will be materially reduced.

Furthermore, the member 20 will be a solid construction provided only with an opening for receiving the ends of the stems 16 and 23, and the formation of the air gap 28, with the result that a very strong and substantial construction will be produced.

While the preferred form of the invention has been herein shown and described, it is to be understood that various changes may be made in the details of construction and in the combination and arrangement of the several parts, within the scope of the claims, without departing from the spirit of this invention.

What is claimed as new is:-

1. A spark plug embodying an insulating core, an insulating member of substantial thickness supported by the end of the core, a central conductor passing through the core and into said member, and a centrally disposed stem passing into the said member and terminating short of the extremity of said conductor to form therewith a spark gap within the said member, and interengaging locking means between the said member and each of said conductor and stem, for locking the conductor and stem against rotation with respect to said member.

2. A spark plug embodying an insulating core, a member constructed of a phenolic condensation product supported by the end of the core, a central conductor passing through the core and into said member, a centrally disposed stem passing into the said member and terminating short of the extremity of said conductor to form therewith a spark gap within the said member, and interengaging means between said member and said stem and conductor for locking said member, stem and conductor against relative movements.

3. A spark plug embodying an insulating core, a member constructed of a phenolic condensation product supported by the end of the core, a central conductor stem passing through the core and into said member, a centrally disposed stem passing into the said member and terminating short of the extremity of said conductor stem to form therewith a spark gap within the said member, a flange on one of said stems, extending therearound and projecting between the proximate faces of the core and said member, one of the contacting faces being provided with a projection and the other with a recess receiving the projection to maintain the member and core against relative rotation.

4. A spark plug embodying an insulating core, a member constructed of a phenolic condensation product supported by the end of the core, a central conductor passing through the core and into said member, a centrally disposed stem passing into the said member and terminating short of the extremity of said conductor to

form therewith a spark gap within the said member, a circumferential flange on the stem and conductor intermediate the extremities thereof, said flanges contacting opposite faces of said member, and locking means between the flanges and the adjacent faces of said member for maintaining the member and stems against relative rotation.

5. In a spark plug, a structure providing a threaded stem and a circumferential flange intermediate the extremities thereof, in combination with a core and a member mounted upon the end of the core, the ends of the stem being threaded into the core and the said member with said flange therebetween, the contacting faces of the flange and the said member being provided one with projections and the other with recesses into which the projections extend to maintain the parts against relative axial displacement.

6. In a spark plug, a structure providing a threaded stem and a circumferential flange intermediate the extremities thereof, in combination with a core of insulating material, and a cap member of considerable and substantially uniform thickness having an opening therethrough, and stem threaded into the ends of said opening with the proximate ends of the stems in alignment and terminating short of each other to form an air gap therebetween and within said member.

7. In a spark plug, a structure providing a threaded stem and a circumferential flange intermediate the extremities thereof, in combination with a core of insulating material, a cap member of considerable and substantially uniform thickness having an opening therethrough, and stems threaded into the ends of said opening with the proximate ends of the stems in alignment and terminating short of each other to form an air gap therebetween and within said member, said cap member being formed of a phenolic condensation product.

8. In a spark plug, a structure providing a threaded stem and a circumferential flange intermediate the extremities thereof, in combination with a core of insulating material, a cap member of considerable and substantially uniform thickness having an opening therethrough, stems threaded into the ends of said opening with the proximate ends of the stems in alignment and terminating short of each other to form an air gap therebetween and within said member, a circumferential flange intermediate the end of each of said stems and contacting the ends of said member, said flanges being of a diameter considerably greater than the diameter of the respective stems, and means on the face of each of the flanges for holding the stems and said cap member against relative rotation.
